CARRIAGES FOR USE ON SCAFFOLDS

Bennie A. Guzzardo and Dino Ungaretti, Chicago, Ill.

Application January 18, 1954, Serial No. 404,656

9 Claims. (Cl. 304—1)

The invention relates to portable carriages for supporting materials, such as paint, or tools, such as brushes, on an extensible scaffold for rendering them readily accessible to a workman on different portions of the scaffold, and expediting and facilitating the performance of the work.

One object of the invention is to provide a portable carriage for this purpose, which is usable with a scaffold which is composed of extensibly connected sections having interdigitated bars.

Another object of the invention is to provide a portable carriage for this purpose, which is applicable to scaffolds of different widths and thickness.

Other objects of the invention will appear from the detailed description.

The invention consists in the several novel features which are hereinafter set forth and are more particularly defined by claims at the conclusion hereof.

In the drawings:

Fig. 1 is a perspective view of a carriage embodying the invention on a scaffold composed of interdigitated bars;

Fig. 2 is a central vertical transverse section; and

Fig. 3 is a section taken on line 3—3 of Fig. 2.

The invention is exemplified with an extensible scaffold which is composed of a pair of slidably connected sections, each including longitudinal bars. One section includes a series of bars 10 or slats cross-connected by a bar 13, and the other section includes a series of bars or slats 12 cross-connected by a bar 13. The bars 10 and 11 are interdigitated and relatively slidable to vary the length of the scaffold for use in areas or rooms of different length. The scaffold may be supported on trestles for inside work or on suspension devices, as well understood in the art.

The portable carriage, generally designated 4 for use by a workman, such as a painter, on the scaffold, comprises a frame which includes three symmetrically arranged arms or members supported on rollers adapted to travel lengthwise of the scaffold. A tubular pedestal 5 is fixedly mounted on the central portion of the carriage frame, a post 6 is slidably fitted in said pedestal, and a suitable holder 7 for materials used for cleaning and painting, or tools, such as brushes and scrapers, used in connection with such jobs, is fixedly mounted on the post 6. The holder is adjustable vertically for the convenience of the workman, by sliding the post 6 in the pedestal 5 and fixing it in its assigned position by a set screw 8. The holder 7 is provided with a rim 9 for retaining articles on the holder.

The carriage frame includes a pair of integral arms 15 and 16 which are spaced apart longitudinally at one side of the scaffold, and an arm 17 including an extensible section 18 at the opposite side of the scaffold substantially at the longitudinal center of the carriage. Each of the arms 15 and 16 and the section 18 of arm 17 has connected to its outer end a pair of rollers for supporting and guiding the carriage lengthwise of the scaffold. Each

2

pair of rollers includes an upper roller 24, adapted to ride on the top surface, and a lower roller 26 adapted for rolling contact with the under surface of the scaffold. Each upper roller 24 on the arms 15 and 16 is journaled on a pin 25 which is supported in depending lugs 26 on said arms, and the upper roller 24 on arm 17 is journaled on a pin 27 mounted in depending lugs 28 on the section 18 of arm 17. The pairs of rollers 24 are symmetrically arranged over the scaffold to support and guide the carriage at two points spaced apart longitudinally on one side of the scaffold and at one point on the opposite side of the receptacle. Each lower roll 26 is journaled on a pin 30 mounted in a bracket 34 which is fixed to a rod 35 which extends through one of the lugs 26 on the outer ends of arms 15 and 16 and the extensible section 18 on arm 17. Wing nuts 36 threaded to the upper ends of rods 35 support the brackets 34 for vertical adjustment of the lower rollers 26 to and from the upper rollers for rolling contact with the underside of scaffolds of different thickness. The bracket 34, rods 35 and nuts 36 function as hangers for adjustably supporting the lower rollers 26 from the arms 15 and 16 and section 18 on arm 17. The extensible section 18 is confined in a channel 38 in the arm 17 and a bolt 39 extends through said arm and a slot 40 in extension 18 which extends transversely of the scaffold for adjusting the section 18 of the carriage frame transversely of the scaffold, for adjusting said pair of rolls to travel on the top and bottom of the side margins of scaffolds of different widths. The three upper rollers 24 support the carriage for free rolling movement on the top of and lengthwise of the scaffold. The three lower rollers 26 have rolling engagement with the under side of the scaffold for holding the carriage against upward displacement. Lugs 37 on brackets 34 extend to lap the outer side of the outermost of the lapped portions of bars 10 and 11 of the scaffold for preventing transverse movement of the carriage off the scaffold. When the sections of the platform are extended as shown in Fig. 1, the bars 10 at one end of the scaffold project longitudinally from the adjacent ends of the bars 11 and at the other end of the platform the bars 11 will project longitudinally from the ends of bars 10. This leaves a transverse gap between the outer faces of the outermost bars 10 and 11 at one side margin and one end of the scaffold, and a transverse gap between the outer faces of the outermost bars 10 and 11 at the opposite end and the other side margin of the scaffold. As a result, the carriage will not be held against transverse movement on the scaffold by the lugs 37 on the brackets 34. The rollers 24 and 26 being of sufficient width travel sufficiently close to either end of the scaffold so that the lugs 37 on one of the brackets 34 is alongside of one of these gaps, the carriage, unless otherwise guided, will not be confined against transverse movement on the scaffold. In order to prevent such transverse movement of the carriage when the scaffold is extended, dogs 40 and 41 are pivoted on the carriage, have distal ends 42 which are adapted to ride on a bar of one section and to drop into and fit in the space between contiguous bars in the other section for guiding the carriage on the scaffold. Each dog is provided with shoulder 43 which rides on the contiguous bars when the dog is dropped, and inclines 44 for camming the dog over the end of a bar in the space between contiguous bars as the carriage travels along the scaffold. Rollers 24 and 26 are of sufficient width to span or lap a pair of contiguous bars 10 and 11 of the scaffold so that when the rollers ride off the end of one of said bars in their travel along the scaffold, they will retain rolling engagement with the other of the pair of bars. Foot pieces or pedals 50 are provided on the carriage frame whereby the workmen

can easily push the carriage and the holder thereon to different longitudinal portions of the scaffold.

The operation and use of the carriage will be as follows: the sections of the scaffold will be adjusted to the length desired according to the area to be worked on and suitably supported, as well understood in the art. The carriage which is separate from the scaffold is placed thereon after the bracket 34, roller 26 and rod 35 on the section 18 of arm 17 have been detached from said section so that the frame of the carriage can be placed on the top of the scaffold. The carriage can be dropped on and slipped transversely over the scaffold with one side margin of the scaffold passing between the rollers 26 and 24 on the arms 15 and 16 so that the carriage will be supported on the scaffold. Next, the lower roller 25, bracket 34 and rod 35 are connected to the section 18 of arm 17 and the nut 36 is applied to rod 35 to support said roller 34 under the upper roller 24 on said section. If desired, the section 18 may be left connected to the arm 17 of the carriage frame and adjusted transversely to space the rollers on the arms 15 and 16 and the rollers on said section 18 apart, a sufficient distance to permit the said rollers to clear the sides of the scaffold, and the carriage to be dropped or placed on the top of the scaffold. The section 18 of arm 17 by means of screw 21 and slot 20 are then adjusted transversely so that the rollers 24 and 26 at opposite sides of the carriage will be vertically aligned with the two outermost bars 10 and 11 at the sides of the scaffold. When the bolt 19 is tightened the carriage will have the correct width for travel on and be guided on the scaffold. This adjustment of the section 18 and rollers thereon also provides for varying the transverse spacing between the rollers at the sides of the carriage for the travel of said rollers on the side margins of scaffolds of different widths with each roller positioned to span the two outermost bars 10 and 11 of the scaffold. The lower rollers 26 hold the carriage against upward displacement or tilting on the scaffold and are adjustable by means of rolls 35 and nuts 36 for rolling engagement with the under side of scaffolds of different thickness.

The carriage may be easily rolled from end to end of the scaffold to move the holder 7 with one or more pails of paint or other material and tools, such as brushes or scraper thereon, for convenient reach of the worker at any point along the scaffold where work is to be done. This greatly facilitates the work. During the travel of the carriage when the rollers 26 and 24 span the lapped portions of the two outermost bars 10 and 11 of the scaffold, the lugs 37 will lap the outer sides of the outermost bars and prevent transverse movement of the carriage on the scaffold.

When the sections of the scaffold are extended, as shown in Fig. 1, and before the carriage is rolled sufficiently close to one of the ends of the scaffold to produce a transverse gap between a lug 37 on one of the brackets 34 and the adjacent side portion of the scaffold, the end 42 of one of the dogs 40 or 41 will drop into a space between the bars of one section of the scaffold and hold the carriage against transverse movement on the scaffold. For example, when the carriage is positioned on the scaffold as shown in Fig. 1, end 42 of dog 40 has dropped and is confined between a pair of bars 10 and is effective to hold the carriage against transverse movement after the rollers 24 and 26 on the section 18 pass off the end of the bar 11 between them and ride only on the bar 10. When the carriage is moved to the opposite end of the scaffold, and before the rollers 24 and 26 on arm 16 pass off the end of the bar 10, the dog 41 will drop into a space between a contiguous pair of bars 11 and hold the carriage against transverse movement during the continued travel of the carriage and guide the carriage to travel longitudinally. The upper and lower rollers being of sufficient width

to engage and span the outermost pair of bars 10 and 11 of the lapped bars of the scaffold, they will ride off the outermost one of these bars, and will remain operative at least with a single bar of the scaffold to support or retain the carriage against vertical movement relatively to the scaffold. The table 51 is used to support the material, such as paint, and any tools, such as brushes, scrapers. The carriage may be easily rolled along the scaffold to keep the material and tools within convenient reach of the worker while he works on spaces adjacent to or over different portions of the scaffold. The worker can move the carriage by pressure on one of the pedals 56. This operation and use facilitate and expedite work by the workman on the carriage.

15 The carriage can be readily mounted on the scaffold and removed therefrom for independently storing it for subsequent uses. The upper and lower rollers safeguard vertical displacement of the carriage while it travels on the scaffold and are readily adjustable for travel on scaffolds of different widths and thickness. The holder for the materials and tools is vertically adjustable for the convenience of workers of different heights. The carriage is simple in construction, can be produced at a low cost, and can be made light in weight and is adapted for 20 use on an extensible scaffold composed of interdigitated bars.

The invention is not to be understood as restricted to the details set forth since these may be modified within the scope of the appended claims without departing from 25 the spirit and scope of the invention.

Having thus described the invention what we claim as new and desire to secure by Letters Patent is:

1. A material or tool supporting carriage adapted for longitudinal travel and demountably supported on a portable scaffold composed of sections with interdigitated bars slidable into and out of more or less lapped relation, for varying the length of the scaffold, comprising: a frame with means therein for supporting and moving therewith material or tools for a worker on the scaffold, devices at both sides of the frame for supporting and guiding the frame to travel freely and longitudinally on and substantially from end to end of the scaffold, each of said devices including a pair of vertically spaced rollers having peripheries of sufficient width for engaging the top and bottom faces of a pair of contiguous lapped bars of the scaffold sections and one of said bars when the bars are extended to leave spaces between them, and means for confining the frame transversely on the scaffold, demountably connected to the frame, to permit removal of the carriage from the scaffold.

2. A material or tool supporting carriage adapted for longitudinal travel and demountably supported on a portable scaffold composed of sections and interdigitated bars slidable into and out of more or less lapped relation, for varying the length of the scaffold, comprising: a frame with means thereon for supporting and moving therewith material or tools for a worker on the scaffold, devices at both sides of the frame for supporting and guiding the frame to travel freely and longitudinally on and substantially from end to end of the scaffold, each of said devices including an upper roller journaled on the frame, a hanger on the frame and at one side of the scaffold, and a lower roller journaled on the hanger and spaced vertically from the upper roller, said upper and lower rollers having peripheries of sufficient width for engaging the top and bottom faces of a contiguous pair of bars of the sections when they are lapped and one of said bars extended to leave spaces between said bars, the hangers being adapted to confine the frame transversely on the scaffold, one or more of said hangers being detachable from the frame for placement of the carriage on and permitting its removal from the scaffold.

3. A material or tool supporting carriage adapted for longitudinal travel and demountably supported on a portable scaffold composed of sections with interdigitated

bars slidable into and out of more or less lapped relation, for varying the length of the scaffold, comprising: a frame with means thereon for supporting and moving therewith material or tools for a worker on the scaffold, devices at both sides of the frame for supporting and guiding the frame to travel freely and longitudinally on and substantially from end to end of the scaffold, each of said devices including an upper roller journalled on the frame, a hanger on the frame and at one side of the scaffold, and a lower roller journalled on the hanger and spaced vertically from the upper roller, said upper and lower rollers having peripheries of sufficient width for engaging the top and bottom faces of a contiguous pair of bars of the sections when they are lapped and one of said bars extended to leave spaces between said bars, the hangers being adjustable vertically on the frame for vertically spacing the lower rollers for travel on scaffolds of different thickness, and adapted to confine the frame transversely on the scaffold, one or more of said hangers being detachable from the frame for placement of the rollers on and permitting their removal from the scaffold.

4. A material or tool supporting carriage adapted for longitudinal travel and demountably supported on a portable scaffold composed of sections with interdigitated bars slidable into and out of more or less lapped relation, for varying the length of the scaffold, comprising: a frame with means therein for supporting and moving therewith material or tools for a worker on the scaffold, devices at both sides of the frame for supporting and guiding the frame to travel freely and longitudinally on and substantially from end to end of the scaffold, each of said devices including a pair of vertically spaced rollers having peripheries of sufficient width for engaging the top and bottom faces of a pair of contiguous lapped bars of the scaffold sections and one of said bars when the bars are extended to leave spaces between them, and a dog movably supported on the frame provided with a terminal for dropping into a space between the bars of the sections and confining the carriage transversely when the scaffold is extended and one of the hangers passes beyond the end of its contiguous side bar of the scaffold.

5. A material or tool supporting carriage adapted for longitudinal travel on and demountably supported on a portable scaffold composed of sections with interdigitated bars slidable into more or less lapped relation for varying the length of the scaffold, comprising: a frame having means thereon for supporting and moving therewith material or tools for a worker on the scaffold and including a pair of arms extending transversely to one side of the scaffold and a single arm extending transversely to the opposite side of the scaffold, devices on the outer ends of the arms for supporting and guiding the frame to travel freely and longitudinally on and substantially from end to end of the scaffold, each of said devices including a pair of vertically spaced rollers having peripheries of sufficient width for engaging the top and bottom of a pair of contiguous bars when they are lapped and one of said bars of the sections are extended to leave spaces between said bars, and means for confining the frame transversely on the scaffold demountably connected to the frame permitting removal of the carriage from the scaffold.

6. A material or tool supporting carriage adapted for longitudinal travel on and demountably supported on a portable scaffold composed of sections with interdigitated bars slidable into more or less lapped relation for varying the length of the scaffold, comprising: a frame having means thereon for supporting and moving therewith material or tools for a worker on the scaffold and including a pair of arms extending transversely to the opposite side of the scaffold, devices on the outer ends of the arms for supporting and guiding the frame to travel freely and longitudinally on and substantially from end to end of the scaffold, each of said devices including a pair of vertically spaced rollers having peripheries of sufficient width for engaging the top and bottom faces of a pair of contiguous

bars when they are lapped and one of said bars of the sections are extended to leave spaces between said bars, and means for confining the frame transversely on the scaffold demountably connected to the frame permitting removal of the carriage from the scaffold.

7. A material or tool supporting carriage adapted for longitudinal travel on and demountably supported on a portable scaffold composed of sections with interdigitated bars slidable into more or less lapped relation for varying the length of the scaffold, comprising: a frame having means thereon for supporting and moving therewith material or tools for a worker on the scaffold and including a pair of arms extending transversely to one side of the scaffold and a single arm extending transversely to the opposite side of the scaffold, devices on the outer ends of the arms for supporting and guiding the frame to travel freely and longitudinally on and substantially from end to end of the scaffold, each of said devices including an upper roller journalled on the arm, a hanger on the arm and at the side of the scaffold, a lower roller journalled on the hanger, the upper and lower rollers having peripheries of sufficient width for engaging the top and bottom face of a contiguous pair of bars of the sections when they are lapped and one of the bars when the sections are extended to leave spaces between said bars, the hangers being adapted to confine the frame transversely on the scaffold, one or more of said hangers being detachable from its arm for placement of the carriage on and permitting its removal from the scaffold.
- 10 8. A material or tool supporting carriage adapted for longitudinal travel on and demountably supported on a portable scaffold composed of sections with interdigitated bars slidable into more or less lapped relation for varying the length of scaffold, comprising: a frame having means thereon for supporting and moving therewith material or tools for a worker on the scaffold and including a pair of arms extending transversely to one side of the scaffold and a single arm extending transversely to the opposite side of the scaffold, devices on the outer ends of the arms for supporting and guiding the frame to travel freely and longitudinally on and substantially from end to end of the scaffold, each of said devices including an upper roller journalled on the arm, a hanger on the arm and at the side of the scaffold, a lower roller journalled on the hanger, the upper and lower rollers having peripheries of sufficient width for engaging the top and bottom faces of a contiguous pair of bars of the sections where they are lapped and one of the bars when the sections are extended to leave spaces between said bars, the hangers being adapted to confine the frame transversely on the scaffold, one or more of said hangers being detachable from its arm for placement of the carriage on and permitting its removal from the scaffold, and vertically adjustable connections between the hangers and the arms for spacing the lower rollers for travel on the bottom faces of the side bars of scaffolds of different widths.
- 15 9. A material or tool supporting carriage adapted for longitudinal travel on and demountably supported on a portable scaffold composed of sections with interdigitated bars slidable into more or less lapped relation for varying the length of scaffold, comprising: a frame having means thereon for supporting and moving therewith material or tools for a worker in the scaffold and including a pair of arms extending transversely to one side of the scaffold and a single arm extending transversely to the opposite side of the scaffold, devices on the outer ends of the arms for supporting and guiding the frame to travel freely and longitudinally on and substantially from end to end of the scaffold, each of said devices including an upper roller journalled on the arm, a hanger on the arm and at the side of the scaffold, a lower roller journalled on the hanger, the upper and lower rollers having peripheries of sufficient width for engaging the top and bottom faces of a contiguous pair of bars of the sections when
- 20 75

they are lapped and one of the bars when the sections are extended to leave spaces between said bars, the hangers being adapted to confine the frame transversely on the scaffold, one or more of said hangers being detachable from its arm for placement of the carriage on and permitting its removal from the scaffold, and a pair of dogs pivotally mounted on the frame, provided with terminals adapted to travel on the top face of a bar, and to drop into spaces between contiguous bars at the ends of the scaffold respectively when the hangers at the respective 10 sides of the frame travel longitudinally beyond the ends of contiguous side bars of the scaffold.
